(57) **CLAIM**

The ornamental design for a multi-depth positive airway pressure pillow, as shown and described.

DESCRIPTION

FIG. 1 is a front perspective view of a multi-depth positive airway pressure pillow according to my design;

FIG. 2 is a front elevational view thereof;

FIG. 3 is a top elevational view thereof;

FIG. 4 is a bottom elevational view thereof;

FIG. 5 is a back elevational view thereof;

FIG. 6 is a left side elevational view thereof; and,

FIG. 7 is a right side elevational view thereof.

The broken lines represent stitching, which forms a part of the claimed design.
